UNITED STATES PATENT OFFICE.

EMILE HARDY, OF NEW YORK, N. Y.

DESIGN FOR A CLOCK-FRAME.

SPECIFICATION forming part of Design No. 30,577, dated April 18, 1899.

Application filed March 22, 1899. Serial No. 710,100. Term of patent 3½ years.

To all whom it may concern:

Be it known that I, EMILE HARDY, a citizen of the United States of America, and a resident of New York, State of New York, have 5 invented and produced a new and original Design for Clock-Frames, of which the following is a specification, reference being had to the accompanying drawing, forming part thereof.

10 The drawing is a full front view of a clock-frame, showing my new design.

As shown in the drawing, the leading features of my design comprise an approximately cylindrical clock-holder portion *a*, having a 15 central circular opening *b* to receive a suitably-shaped clock and bordered mainly by two female figures *c* and *d*, one on each side

of the holder, and by an intermediate ornamental top extension *e*. This main holder portion *a* is supported upon a stem or neck *f*, rising centrally from a rectangular base *g*. The several portions are suitably ornamented with scrollwork, beading, and carving, as shown.

What I claim is—

The design for a clock-frame substantially as shown and described.

Signed by me, at New York, N. Y., this 18th day of March, 1899.

EMILE HARDY.
